UNITED STATES PATENT OFFICE.

HARRY L. BARNARD, OF MOUNT POCONO, AND CHARLES A. NAUMAN, JR., OF CRESO, PENNSYLVANIA; SAID NAUMAN ASSIGNOR TO BARNARD.

WAGON-BODY BRACE.

Application filed September 11, 1922. Serial No. 587,441.

To all whom it may concern:

Be it known that we, HARRY L. BARNARD AND CHARLES A. NAUMAN, Jr., citizens of the United States, residing, respectively, at 5 Mount Pocono and Cresco, in the county of Monroe and State of Pennsylvania, have invented certain new and useful Improvements in Wagon-Body Braces; and we do declare the following to be a full, clear, and 10 exact description of the invention, such as will enable others skilled in the art to which it appertains to make and use the same.

This invention relates to a brace for use in connection with the body of a vehicle such as 15 a truck used for hauling heavy loads, and one object of the invention is to provide a brace which is so constructed that when the body portion is swung upwardly, it will be prevented from twisting. It often happens 20 that when a truck body is loaded, greater weight will be placed at one side than the other and this will cause twisting of the body either during hauling of the load from one place to another or during tilting of the 25 body to cause the load to pass out through the open rear end of the body.

Another object of the invention is to provide a brace which is so constructed that it may be put in place in connection with a 30 conventional structure of body support and firmly held in place.

This invention is illustrated in the accompanying drawings, wherein:

Figure 1 is a perspective view showing a 35 vehicle body provided with the improved bracing means.

Figure 2 is a top plan view of the support for the vehicle body or box with the brace shown in place.

Figure 3 is a longitudinal sectional view 40 taken along the line 3—3 of Fig. 2.

Figures 4 and 5 are transverse sectional views taken along the lines 4—4 and 5—5 respectively of Fig. 2.

Figure 6 is a fragmentary top plan view 45 showing a modified construction.

Figure 7 is a transverse sectional view taken along the line 7—7 of Fig. 6.

Figure 8 is a longitudinal sectional view 50 taken along the line 8—8 of Fig. 6.

Figure 9 is a fragmentary perspective view showing a modified construction of brace.

This brace is for use in connection with a 55 conventional structure of vehicle of the

dumping type. Referring to Fig. 1, it will be seen that the body or box 1 of this vehicle rests upon cross bars 2 which are firmly secured to longitudinally extending side bars 3. These side bars 3 are pivotally mounted 60 by means of bearing brackets 4 which are carried by longitudinally extending bars 5. A conventional construction of hoisting means H has been shown for swinging the forward end portion of the wagon box 1 upwardly to permit material in the wagon box to pass out through the rear end thereof. This construction as previously stated is a conventional construction and it is to be understood that in order to apply the brace, 65 it is only necessary to provide a box-carrying structure including the side bars 3 and preferably the cross bars 2. The bracing bars 6 are formed from I-beams which in the present form are of substantially the same 70 size as the I-beams from which the side bars 3 are formed. These bracing bars 6 are bent to provide end portions 7 which extend parallel to the end portions of the bars 3 and are further bent to provide intermediate 75 portions which extend towards each other and at a point intermediate the length and width of the wagon box support extend parallel. These parallel sections 8 and the end portions 7 are provided with openings 80 so that securing bolts 9 which are passed through openings formed in the blocks 10 and 11 may be passed through the bracing bars and through the side bars 3 and firmly hold the filler blocks 10 and 11 in place. By 85 having these filler blocks positioned between the sections 8 and between the end portions 7 and end portions of the bars 3, the bracing bars will be firmly held in the desired position and will be prevented from having 90 longitudinal movement or vertical movement. If desired, the bracing bars may be riveted or otherwise secured to the cross bars 2.

In Figs. 6, 7 and 8 there has been shown a 100 slightly modified construction in which the side bars 3 and the bracing bars 6 are formed of channel iron instead of being formed of I-beams. The blocks 10 which are positioned between the side bars 3 and the end portions 7 of the bracing bars are secured by bolts 9 after the manner shown in Figs. 2 to 105 5 but the blocks 11 in addition to being secured by the bolts 9 is also held in place by bolts 12. The flanges of the bracing bars 110

extend outwardly and the flanges of the side bars 3 extend inwardly. Therefore, the flanges of these bars will extend above and below the blocks 10. The web portion of the 5 bracing bars 6 extend between the blocks 11 and the bolts 9 pass through the blocks 11 and web portions of the bars 6 and the bolts 12 extend through openings which will be formed in the web of the bars. Washers 13 10 have been placed upon the upper end portions of these bolts 12 so that they will overlap the flanges of the bars. If desired, similar washers may be placed upon the lower end portions of these bolts before the securing 15 nuts are put in place. It should be noted that instead of having a single block 11 for filling the space between the flanges of the intermediate portions of the bars 6 in this form, there has been provided two blocks. 20 In Fig. 9, there has been provided a further modification in which the bracing bars 6 have their flanges extending inwardly instead of outwardly. A single block 11 can therefore be secured between the intermediate 25 portions 8 of the bracing bars. In order to strengthen the bracing bars, smaller I-beams 14 may be secured against the webs of the bracing bars between the upper and lower flanges thereof. Therefore, the bracing 30 bars will be very firmly braced and any tendency towards bending prevented. When the braces are put in place and secured with the blocks 10 and 11 in place, the end portions of the bracing bars will be secured to 35 the end portions of the side bars 3. Therefore, when the wagon box is swung upwardly to permit passing of material through the rear end thereof, the body will be firmly braced and will be prevented from twisting 40 and thus becoming warped and prevented from resting properly when again swung downwardly to the normal position.

A very efficient brace has therefore been provided for preventing the vehicle body or

box from becoming twisted out of shape by 45 heavy loads which are unevenly distributed in the body.

We claim:

1. In combination with a tilting support for end dumping truck body, said support 50 including longitudinally extending side bars pivotally mounted at their rear ends, of bracing bars extending longitudinally of said support between said side bars and having their end portions extending parallel 55 to the side bars and their intermediate portions converging towards the center of said support and provided intermediate the length of the support with portions extending parallel to each other, said side 60 bars and bracing bars being provided with upper and lower flanges, filler blocks positioned between the flanges of the end portions of the bracing bars and side bars and between the flanges of the central portions of 65 the bracing bars, and fasteners and fastener bolts passing through said bars and filler blocks.

2. In combination with a tilting support for an end dumping truck body, said support 70 including longitudinally extending side bars pivotally mounted at their rear ends, of bracing bars extending longitudinally of said support between said side bars and having their end portions extending parallel to 75 the side bars and their intermediate portions converging towards the center of said support and provided intermediate the length of the support with portions extending parallel to each other and longitudinally of the support, means securing the end portions of the bracing bars to said side bars, and means securing the intermediate portions of the bracing bars to each other. 80

In testimony whereof we have hereunto 85 affixed our signatures.

HARRY L. BARNARD.
CHARLES A. NAUMAN, JR.
